UNITED STATES PATENT OFFICE.

FRANCIS L. WRIGHT, OF NEW DECATUR, ALABAMA.

METALLIC RAILWAY-TIE.

1,117,471.

Specification of Letters Patent. Patented Nov. 17, 1914.

Application filed April 22, 1914. Serial No. 833,725.

To all whom it may concern:

Be it known that I, FRANCIS L. WRIGHT, a citizen of the United States, residing at New Decatur, in the county of Morgan, State of Alabama, have invented certain new and useful Improvements in Metallic Railway-Ties; and I do hereby declare the following to be a full, clear, and exact description of the invention, such as will enable others skilled in the art to which it appertains to make and use the same.

The present invention is directed to improvements in metallic railway ties, and has for its object to so construct a device of this character that the same will be extremely strong, and at the same time will be sufficiently light so that it can be handled easily.

A further object of the invention is to so construct a tie of this type that the rails can be easily and quickly fastened thereto.

With these and other objects in view, this invention resides in the novel features of construction, formation, combination and arrangement of parts to be hereinafter more fully described, claimed and illustrated in the accompanying drawing, in which:

Figure 1 is a top plan view. Fig. 2 is a side elevation. Fig. 3 is an end view. Fig. 4 is a sectional view on line 4—4 of Fig. 1. Fig. 5 is a similar view on line 5—5 of Fig. 1. Fig. 6 is a similar view on line 6—6 of Fig. 1.

Referring to the drawing, the numeral 1 designates the body of the tie, which is rectangular in cross section, said body being molded hollow so as to impart the necessary lightness thereto and at the same time produce a tie which is exceedingly durable. Each side of the body 1 is provided centrally with an opening 2 so that the sand or similar material used in forming the chambers 3 during the casting may be withdrawn from the chambers 3—3, which are divided by the vertical partition 4 which extends longitudinally of the body. The body member has its ends integrally formed with sections 5, said sections being formed with recesses 6, which are disposed in oblique relation so that there will be a recess upon each side of each rail. The said sections 5 are further provided with transverse cleats 7, which are designed to engage the outer edges of the rail flanges so as to prevent lateral movement thereof in outward directions. These sections 5 are formed with chambers 5' with

openings 2 through which the sand used in casting may be withdrawn. Wooden blocks 8 are provided and are driven into the recesses 6 so that the spikes 9 may be driven into the blocks with their heads in engagement with the rail flange base, thus securely fastening the rails to the tie.

The base of each recess is provided with an opening 10, which is for the purpose of permitting a spike to be removed in case the same could not be pulled in the usual manner, it being of course obvious that to remove a spike through one of the openings 10 it will be necessary to drive one of the same through the block 8. The ends of the body 1 are hollowed, as at 12, thus lightening the tie and at the same time giving it the proper length. Transverse slots 13 are formed in the upper walls of the hollows 12 and have notches 14 formed in their outer walls, which may be engaged by picks or other tools so that it may be pulled properly under the rails.

To prevent lateral shifting of the tie in respect to the road-bed or ballast the bottom is provided with a plurality of transversely disposed corrugations 15.

From the foregoing description it will be seen that a metallic tie has been provided which is constructed in such a manner that the rails may be easily and quickly applied thereto, and further that a tie has been provided which with the exception of the wooden blocks is formed from a single bulk of metal.

What is claimed is:

A railway tie having its body formed with centrally disposed spaced chambers, a partition separating the chambers, hollow end sections forming a part of the body and spaced from each other by said chambers, said partition having its ends formed integral with the end sections, transverse cleats formed upon the upper surfaces of the end sections, said end sections having recesses formed therein, wooden blocks insertible in the recesses for receiving the usual spikes to hold the rails upon the tie with their outer base flanges engaging the cleats.

In testimony whereof, I affix my signature, in the presence of two witnesses.

FRANCIS L. WRIGHT.
